STRAIGHT EDGE

Filed March 24, 1934

Fig. 1.

UNITED STATES PATENT OFFICE

2,006,285

STRAIGHT-EDGE

Max Kurt von Zimmermann, Elkhart, Ind.

Application March 24, 1934, Serial No. 717,246

5 Claims. (Cl. 33—76)

This invention relates to straight-edges, and more particularly to straight-edges which are integral with a drawing board.

This application is a continuation in part of my copending application bearing Serial Number 701,551, filed December 8, 1933.

One object of my invention is to provide a straight-edge, parallel with an adjacent edge of the drawing board, capable of projection above the board when in use or of retraction into the board when not in use; another object of this invention is to provide means for yieldingly locking said straight-edge in a raised or lowered position with respect to said board. Other objects and advantages of this invention will appear from the following specification and the drawing in which—

Figure 1 is a top plan view of one type of board embodying my invention; Fig. 2 is a side view along the line 2—2 of Fig. 1; Fig. 3 is a fragmentary side sectional view along the line 3—3 on Fig. 1, showing the straight-edge and its supporting means when said straight-edge is in a lowered position; Fig. 4 is a view similar to that of Fig. 3, but showing the straight-edge in a raised position; Fig. 5 is a sectional view along the line 5—5 of Fig. 4, showing the locking means in more detail; and Fig. 6 is a vertical sectional view along the line 6—6 of Fig. 4.

In the illustrations the drawing or writing board is indicated by the reference numeral 10. This board has in connection therewith straight edges 11 and 12, preferably of metal. These straight-edges are parallel to their adjacent edges of the board 10 and are perpendicular to each other. Both straight-edges perform a similar function and are similarly mounted in the board so that we shall consider only the mounting of one of them, that of the straight-edge 12. The straight-edge 12 lies in a recess or groove 13 in the board 10, this groove having sufficient depth that the straight-edge may sink into it until its upper surface is flush with or below the level of the surface of the board 10. Near the ends of this groove, the board has holes 14 bored therethrough which holes contain metal inserts 15 which have a driving fit therein. These metal inserts are also slotted or grooved so that the straight-edge 12 recesses therein. Sloping slots 16 in the straight-edge 12 engage pins or members 17 in the metal inserts 15, which members are positioned transversely with respect to the straight-edge and form supports therefor.

The straight-edge 12 has near the center thereof notches 18 and 19 adapted to cooperate

with a yieldingly locking means, as a metal spring 20. This metal spring is carried in a metal plug 21 which has a driving fit in a hole 22 through said board 10. The metal plug 21 has near its base a pin 23 forming a supporting means about which the spring 20 is coiled in order to retain it in its proper relation with the plug 21 and the straight-edge 12.

In this form of my device the straight-edge is raised or lowered by applying a manual force tending to move it longitudinally. The longitudinal movement acts through the slope of the slots 16 to change the vertical level of said straight-edge. The straight-edge is held in the raised or lowered position by the yielding engagement of the spring 20 with one of the notches 18 and 19. It is understood, of course, that other notches may be employed if it is desired to lock the straight-edge at any intermediate position.

This form of support for the straight-edge is very effective in that it does not permit the straight-edge to become separated from the board. The straight-edge is at all times immediately available for use with a triangle or other drafting aid, yet it may be lowered to its recessed position and present no obstacle to the use of other straight-edge devices as T-squares or the like. The notch and spring locking means in combination with the sloping slots provide a supporting means for the straight-edge which holds it in a desired position irrespective of the vertical pressures which may be applied to it in the ordinary course of drafting, yet a relatively easy manual longitudinal pressure serves to raise or lower the straight-edge.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I regard as new, and desire to secure by Letters Patent, is:

1. A board of the character described, having in combination: a groove in said board; a straight-edge adapted to lie in said groove; diagonally sloping slots in said straight edge; and members on said board adapted to be engaged by said slots, whereby longitudinal movement of said straight-edge effects a change in the vertical level thereof.

2. A board of the character described, having in combination: a groove in said board; a straight-edge adapted to lie in said groove at a plurality of different levels, at least one level being flush with or below the surface of said board; diagonally sloping slots in said straight-edge; members on said board adapted to be engaged by said slots, whereby longitudinal movement of said straight-edge effects a change in the vertical level thereof; and means for yieldingly locking said straight-edge at a plurality of different vertical levels.

3. A board of the character described, having in combination: a groove in said board; a straight-edge adapted to lie in said groove at a plurality of different levels, at least one level being flush with or below the level of said board; a diagonally sloping slot in said straight-edge; an insert in said board having a pin therein adapted to be engaged by said slot, whereby longitudinal movement of said straight-edge effects a change in the vertical level thereof; a notch in said straight-edge; and means adapted to yieldingly engage said notch, whereby said

straight-edge may be locked at a desired vertical level.

4. A board of the character described, having in combination: a groove in said board; a straight-edge adapted to lie in said groove at a plurality of different vertical levels, at least one level being flush with or below the surface of said board; a notch in said straight-edge; and means adapted to yieldingly engage said notch, whereby said straight-edge may be locked at a desired vertical level.

5. A board of the character described, having in combination: a groove in said board; a straight-edge adapted to lie in said groove at a plurality of different vertical levels, at least one level being flush with or below the surface of said board; a metal plug in said board adjacent to said straight-edge; a yielding spring projecting from said plug; and a notch in said straight-edge adapted to be engaged by said spring, whereby said straight-edge may be locked at a desired vertical level.

MAX KURT VON ZIMMERMANN.
